UNITED STATES PATENT OFFICE

GEORGE C. BOSSON, JR., OF CAMBRIDGE, MASSACHUSETTS

COMBINED TENT AND HOOD-GARMENT

Application filed October 7, 1931. Serial No. 567,377.

This invention relates to convertible tents and aims to provide a combined shelter tent and hooded cloak of the poncho type which may constitute a part of the regulation equipment of a soldier. Further objects are to provide a quickly and easily convertible construction of simple design, possessing wearing comfort and affording protection to the head as well as the body when used as a cloak. Other objects relate to details of construction and will be apparent from a consideration of the following description and accompanying drawing which exemplifies one embodiment of the invention chosen for the purpose of illustration.

In the drawing:

Fig. 1 is a perspective view of a convertible shelter tent embodying my invention;

Fig. 2 is a fragmentary view of the inner side of a lateral flap or shelter half;

Fig. 3 is a section on the line 3—3 of Fig. 2; and

Fig. 4 is a front view showing the manner of using the shelter half as a poncho.

The shelter or "pup" tent shown in Fig. 1 comprises two shelter halves made of a light and flexible fabric rendered water and gas proof, each having a lateral or side flap 11 and a rear flap 12, the construction being similar to the regulation army shelter half.

In accordance with my invention I provide a transverse slit or opening 13 in the lateral flap 11, preferably midway between the lateral edges and adjacent to the junction of the lateral and rear flaps. A two-ply closure flap 14 is stitched or otherwise secured along its upper longitudinal edge to the outer side of the flap 11 adjacent to the opening 13 and is adapted to be buttoned over the opening to provide a closure therefor when the shelter half is in erected position as shown in Fig. 1.

A pocket-like element or hood 15 is secured to the marginal portions about the opening 13, as shown in Figs. 2 and 3, and hangs in depending position on the inner side on the shelter half when in erected position. As shown in Fig. 3, suitable reinforcing strips 16 and 17 and reinforcing tapes 18 and 19 are preferably secured around opening 13 by

the run seams 20 and 21 which pass through the reinforced edges of the hood 15 and serve to secure the hood to the lateral flap 11. The run seam 22 passes through the upper longitudinal edge of the flap 14 and the opposite end of the reinforcing strip 16, thus securing the flap 14 and the opposite end of strip 16 to the flap 11, the corresponding end of reinforcing strip 17 being secured to the lateral flap 11 by seam 23. The seam 24 extends entirely around the flap 14 and secures the adjacent edges of its two plies together.

A plurality of snap fastener elements 25 are preferably used to hold the closure flap 14 over the opening 13, one part of each of these elements being secured to the closure flap adjacent to its lower longitudinal edge, the complementary parts being carried by the lateral flap 11 adjacent to the edge of the reinforcing strip 17, as shown in Fig. 3.

The pocket-like element or hood 15 has an opening 30 in its front, which opening extends to and communicates with the opening 13. The marginal portion about the opening 30 is provided with a reinforcing band or strip 31 which is secured to the hood by spaced seams 32 which define a passage for the draw string 33 by means of which the effective size of the opening 30 can be varied.

When the shelter half is in erected position, as in Fig. 1, the hood 15 normally hangs in a depending position on the inner side of the lateral flap 11, and provides a readily accessible wall pocket which may be conveniently used to hold various articles.

When the shelter half is to be used as a poncho, the closure flap 14 is unfastened and the pocket-like element 15 is turned inside out through the opening 13 to provide a hood which may be drawn over the head as shown in Fig. 4, the lateral flap 11 and side flap 12 providing a cloak about the body. By means of the draw string 33 the size of the opening in the front of the hood may be varied and the hood may be drawn about the head and face. This feature offers a particular advantage to a soldier engaged in active warfare in that the hood affords protection to the normally exposed portions of the head against poisonous gases, such as mustard gas,

which attack the skin and cause severe burns.

It should be understood that the present disclosure is for the purpose of illustration only and that this invention includes all modifications and equivalents which fall within the scope of the appended claims.

I claim:

1. A tent of the character described comprising a shelter half adapted to be used as a cloak or poncho, said shelter half having an elongated opening through which the head may pass when used as a poncho, and a permanently attached hood secured to the marginal portion about said opening, the hood having an opening in its front and a draw string associated therewith to vary the effective size of said latter opening, said hood being adapted to hang in a depending position on the inside of said shelter half when in erected position, and being adapted to be turned inside out to provide a covering about the head when said shelter half is used as a poncho.
2. A tent of the character described comprising a shelter half adapted to be used as a cloak or poncho, said shelter half having an elongate opening through which the head may pass when used as a poncho, a flap adjacent to said opening to provide a closure therefor, and a permanently attached hood secured to the marginal portion about said opening, the hood having an opening in its front and a draw string associated therewith to vary the effective size of said latter opening, said hood being adapted to hang in a depending position on the inside of said shelter half when in erected position, and being adapted to be turned inside out to provide a covering about the head when said shelter half is used as a poncho.

40 Signed by me at Boston, Massachusetts, this fifth day of October, 1931.

GEORGE C. BOSSON, Jr.
